UNITED STATES PATENT OFFICE.

FRED ELLIS, OF SALEM, OREGON.

CENTRIFUGAL CASTING MACHINE.

Application filed April 13, 1921. Serial No. 460,899.

To all whom it may concern:

Be it known that I, FRED ELLIS, a citizen of the United States, and resident of Salem, county of Marion, and State of Oregon, have 5 invented a new and useful Centrifugal Casting Machine, of which the following is a specification.

The present invention relates to improvements in centrifugal casting machines such 10 as are principally used by the dental profession in casting inlays, clasps, crowns, bridges, saddles and the like and its object is to present an improved casting machine in which the actual laws of nature with reference 15 to centrifugal force are more closely observed than in the present casting machines and more satisfactory results obtained thereby. A further object of the invention is to provide a centrifugal casting machine 20 in which the rotating shaft is pivotally mounted in the spring-actuated means for rotating it so that the shaft may continue to spin after the tension of the spring has been exhausted. Further objects and advantages 25 will appear as the description proceeds.

I attain these objects by means of the mechanism illustrated in the accompanying drawing, in which Figure 1 represents a plan view of my device, Figure 2 a vertical cross- 30 section through the same along line II—II of Figure 1, and Figure 3 a horizontal section through the same along line III—III of Figure 2.

Referring to the drawing in detail the 35 reader will see that in my centrifugal casting device the shaft 1 is arranged centrally within and co-axially with the cylinder 2 rigidly secured to a base plate 3, which latter is adapted to be fastened to a support, 40 as a table for instance, by means of the screws 4. The shaft is pointed at the bottom and its point is resting on the base plate. A horizontal plate 6 extending through the cylinder and secured to the wall of the same, 45 as shown at 7, is provided with a central perforation 8, which, together with a vertically aligned perforation 9 in the top plate 11 removably secured to the cylinder as shown at 12, holds the shaft in a vertical position. 50 Rotary motion is imparted to said shaft by means of the coil spring 14, one end of which is secured to the wall of the cylinder by means of the screw 16 while the other end is screwed to a sleeve 17 on the shaft 1 55 by means of the screw 18. The sleeve 17 is rotatable on the shaft and is supported on

a collar 19 rigidly secured to the shaft. A second sleeve 21 is secured to the shaft 1 immediately above the sleeve 17 by means of the set screw 22. The two sleeves 17 and 21 are arranged with reference to each other so that the upper may rotate on the lower in one direction but not in the other. I accomplish this object by means of the ball 23 which is adapted to disappear altogether in 60 a vertical recess 24 in the bottom of the upper sleeve 21, so that ordinarily it would not interfere with the rotation of the upper sleeve on the lower one, but would only rest on the surface of the lower sleeve describing 65 a circle on said surface. But on its circular path the ball meets with a recess 26 in the top of the sleeve 17. The latter recess occupies only a small part of said circular path, starts with an inclining plane 70 and grows deep enough to take up a considerable part of the ball, at the other end. In Figure 2 the ball is shown as being partly sunk into the recess of the lower sleeve. If the shaft 1 is turned clockwise, the upper 75 sleeve 21, being keyed to the same by the set screw, will rotate with the same and carry along the ball, which, as shown in the drawing, will on this rotation sink a trifle deeper into the recess in the sleeve 17 until 80 it reaches its end. Then it will carry the sleeve 17 along and cause the same to rotate and thereby wind the spring. When the spring is released by the tripping device to be described hereinafter, it will cause the 85 lower sleeve 17 to rotate counter-clockwise and the ball, being actuated by the same end of the groove it was bearing on before, causes the upper sleeve to partake of the rotation of the lower one. When the tension of the spring is exhausted the latter 90 will act as a brake on the lower sleeve 17, causing the same to stop rotating. But this brake action of the spring will not interfere with the rotation of the upper sleeve of the 95 shaft, because, when the lower sleeve stops, the ball is at liberty to ascend the inclined plane in the lower sleeve and disappear in the upper sleeve altogether, thereby enabling the upper sleeve and the shaft to spin until 100 the rotary force imparted to the same by the spring action is completely spent.

Underneath the collar 19 there is supported on the shaft a ratchet wheel 31 adapted to be engaged by a pawl 32 extending into the cylinder from the outside and pivoted between two lips 33 extending from the 110

outer surface of the cylinder. The pawl is adapted to lock and release the ratchet wheel and thereby the spring by being swung on its pivot 35.

- 5 The shaft 1 extends beyond the top plate 11 of the cylinder and carries at its upper end a horizontal bar 36, secured thereon by means of two nuts 37. The two arms 38 and 39 of said bar extend into opposite directions.
- 10 The latter carries the casting device, while the former, 38, carries a counter-weight 41 adjustably secured thereto by the stud 42 extending through a slot 43 in said arm and held in place by a nut 44.
- 15 The casting device itself is carried by the extreme end of the other arm 39 and comprises the cylindrical ring 46, known in the particular art as the flask, held in the flask holder 47 and the crucible 45. The flask holder is adjustably fastened to the arm by means of the bolt 48 and nut 49, a slot 51 in the arm allowing of longitudinal adjustment. The crucible is seated in the channel 52 which latter is slidably fastened to the arm 20
- 25 39 by means of the clasp 53 projecting from the bottom of the channel. The theory of this arrangement is well understood in the art concerned. The flask holds the mold and the crucible holds the material to be molded,
- 30 as gold for instance. The latter is melted by means of a blow-pipe, whereupon the spring is released, which violently rotates the shaft and the two arms and forces the melted metal by centrifugal force into the mold through
- 35 an aperture 54 in the crucible.

On closer observation it will be found, however, that this arrangement alone does not utilize the laws of nature concerned to their best advantage. Assuming that the 40 casting device is set as in Figure 2, a mold being arranged in the flask and the crucible provided with the necessary amount of molten metal. When the shaft commences to rotate now, it will be easily seen that there 45 will be no immediate tendency of the molten metal to be thrown into the mold by centrifugal force. Its first tendency will be to follow the law of inertia and to rise on the rearward surface of the crucible and it is

not until after the centrifugal force is fully developed that the metal begins to flow into the mold. Thus a most precious unit of time is lost before the metal begins to flow in the right direction and to overcome this undesirable feature of the present day casting device. I introduce my elbow 56 into the arm. This elbow allows that part of the arm 39 carrying the casting device to pivot on a pin 57 through a quarter turn in a direction opposite to the rotary direction of the arm at 55 the time the casting is done, as shown in full lines in Figure 1. It will be seen that in this manner the direction of the connecting channel between crucible and mold is changed from a radial one to a tangential one and 60 that this direction becomes radial only under the influence of the centrifugal force of the rotating arm. Under this arrangement the connecting channel is made to follow substantially the same laws that the molten 65 metal has to follow, and the tendency of the molten metal will be toward said path at the very start of the rotation.

I claim:

In a centrifugal casting machine, a base, a 75 vertical cylinder mounted thereon, a vertical shaft centrally supported therein, a sleeve rotatably mounted on the shaft, a spring for actuating the sleeve, a second sleeve rigidly mounted on the shaft in sliding contact with 80 the first sleeve, two co-acting recesses in the contacting surfaces of said sleeves, a ball capable of vertical movement in the upper recess adapted to operatively engage the lower recess when rotating in one direction 85 and idlingly when rotating in the opposite direction so as to prevent and allow, respectively, sliding motion between the sleeves, whereby the spring actuated sleeve may 90 actuate the second sleeve but not stop the same, a ratchet wheel mounted on the shaft within the cylinder and a pawl mounted outside of the cylinder and extending through a slot in the cylinder in engagement with the ratchet for holding the spring under tension 95 and for releasing the same when manually actuated.

FRED ELLIS.
